F. T. POWERS

ETCHING MACHINE

Filed Dec. 23, 1926

UNITED STATES PATENT OFFICE.

FRANK T. POWERS, OF DOUGLASTON, NEW YORK.

ETCHING MACHINE.

Application filed December 23, 1926. Serial No. 156,650.

My invention relates to apparatus used for etching articles of various kinds but more particularly for the etching of metal plates used in printing, such as are prepared for the printing process by photo-mechanical-chemical means and are known as half-tone plates or line cuts.

One object of my invention is to obviate the necessity of the etcher reaching into or stooping over the etching tank in which the process of etching photo-mechanical printing plates is commonly carried on.

Another object is to provide a more convenient rest or carrier for the plate so as to lessen the amount of handling of the plate by the etcher, and to permit the examination of the plate during the process of etching without the necessity of the etcher touching the plate or of getting any of the etching fluid on the hands of the etcher.

I accomplish these and other desirable results, which will become apparent to one skilled in the art of etching plates of the character described upon a study of the description taken together with the accompanying drawings and the claims, by the use of a device which may be adapted for attachment to and for use with etching machines of the tank type which are already installed and in use, or it may be adapted to incorporation in new machines specially constructed to receive it.

I have shown in the accompanying drawings but one form of the several which embody the principle of my invention. Obviously there are other embodiments of the invention which could be used to illustrate it but the one shown is a simple form which is preferred for some applications.

In Figure 1, I have shown a general view of the chosen embodiment of my invention in place in an etching tank and in Figure 2 I have shown a view on the line AA at right angles to the view in Figure 1. Figure 3 shows a detail of a portion of the mechanism and Figure 4 shows alternate simplified form of the mechanism.

In Figure 1, 1 represents the acid resistant tank or receptacle within which the etching process is carried out; 2 is the rotatable paddle wheel which picks up the etching fluid and projects it against the plate to be etched; 3 is the shelf or ledge extending along one end of the etching tank and upon which the plate to be etched is commonly placed; 4 is

the sliding cover of the etching tank by means of which the opening in the top of the tank is closed while the etching operation is going on within the tank. These parts are typical of many of the etching machines now in common use. At 5 is shown a plate carrier of acid resistant material which is attached by means of a bracket 6 to a sleeve 7 which is slidably mounted on a vertical guide 8, which is carried on a base 9 resting on or fastened to the floor. At the top of the vertical guide 8 is mounted a sheave wheel by means of a suitable bracket 10. The moveable parts just described are conveniently counterbalanced by means of a chain or cord 12, one end of which is attached to the slideable sleeve 7, and after passing over the sheave wheel 11 the other end is attached to a counterweight 13 which is of weight approximately equal to the combined weight of the plate carrier 5, the bracket 6, and the sleeve 7. A guide pin 14 fixed to the sleeve 7 and engages a slot 15 in side of the guide 8, which in this case is preferably made cylindrical and hollow. The slot 15 extends vertically along the side of the guide 8 from a point 16 a little below the position of the pin 14 when the plate carrier 5 is in its position within the etching tank 1, up to a point 17 a little above the position of the pin when the plate carrier 5 is moved upwardly until its bottom clears the top of the etching tank. From this point 17 the said slot is in the form of a spiral about the guide 8 and extends around said guide one fourth of its circumference, to the point 18. On the inner projecting end of the guide pin 14 is provided a hole 19 for receiving the chain or cord 12, which, after passing over the sheave wheel 11, is attached to the counterweight 13.

Figure 2 shows the same assembly of parts viewed from the paddle wheel end of the etching chamber on the line AA.

Figure 3 shows in detail the construction and arrangement of the guide pin 14 just described.

Figure 4 shows a simplified form of apparatus which embodies several of the features and accomplishes several of the objects of my invention while at the same time being less costly to construct. In this form the guide 8 is not provided with the slot 15 and the guide pin 14 is omitted. The cord or chain 12 is attached at one end to the sleeve 110

7 at the point 14* and after passing up and over the sheave 11 is attached to the weight 13.

Having described the construction I will now describe the operation of my invention. I will omit the lesser details of the operation of the etching machine itself since this forms no part of my invention and is well understood by those familiar with the art.

It is important, however, to insure a proper understanding of the novelty and convenience to the etcher of my invention, to describe the placing of the plate to be etched in position in the etching machine and the withdrawing of it for inspection during the progress of the operation of etching and at its completion. In etching machines of the type now commonly used this is accomplished by moving the sliding cover 4 so as

20 to open a portion of the top of the etching tank 1. The operator then leans over the tank and places the plate to be etched by hand on the ledge 3. In doing so he exposes himself to the gases and fumes which arise from the opening in the top of the tank and breathes the noxious and irritating gases into his lungs. His hand, with which he places the plate upon the ledge 3, is exposed to the stronger fumes within the tank and

25 to the corrosive acids dripping from the top and down the sides of the tank. But this is not the severest exposure to which the operator is submitted while etching with the common type of machine. When the

30 plate is partly etched it must be frequently examined by the operator, and it must be turned to a new position on its support so that an even etch will be secured. At each of these examinations and turnings the operator

35 leans over the open tank, breathes the fumes, which are extremely obnoxious, and handles a plate wet with corrosive etching fluid and otherwise is exposed to gases, spray and fluid. With my novel device the operator is not subjected to these objectionable conditions. To remove a plate from

40 the tank for examination or for turning or when the etching process is completed, the operator takes hold of the sleeve 7 and, assisted by the action of the counterweight 13,

45 raises the plate carrier 5 to the upper limit of its travel. In this position the lower edge of the plate carrier 5 will be clear of the top of the tank 1, and may be rotated about

50 the vertical guide 8 to bring the plate being etched into convenient position for examination by the operator. With the plain form of vertical guide 8 shown in Figure 4 the operator rotates the plate carrier by

55 hand to bring the plate being etched into the desired position but with the form of guide shown in Figures 1 and 2 the plate carrier 5 is automatically rotated about the vertical guide 8 as the plate carrier ap-

60 proaches the upper limit of its travel.

When the bottom of the plate carrier is raised to a point slightly above the top of the etching tank the guide pin 14 will have traveled upward along the straight vertical slot 15 to the point 17. As the slot at this point changes its direction and extends upwardly in a spiral course around the guide 8 through an angle of 90°, the guide pin 14 will, as the sleeve 7 is moved upwardly above the point 17, cause the sleeve 7, with its attached bracket 6 and plate carrier 5 to rotate through an angle of 90° when the guide pin 14 has reached the top of the slot at the point 18. The plate being etched will then have been removed from the etching position within the etching tank and moved up and rotated into a position most convenient for examination by the etcher, without the etcher having touched any portion of the plate or apparatus which is wet with the etching fluid. Nor has the etcher been obliged to put his hand within the etching tank filled with corrosive and skin irritating fumes. Nor has he bent over the tank or breathed the noxious fumes arising therefrom. The reversal of the above described operation place the plate to be etched back in the etching tank with like freedom from exposure of the etcher to the fumes within the tank. Should it be desired to rotate the plate carrier through an angle greater than 90° at the upper portion of its travel, the spiral portion of the slot 15 may be extended around the vertical guide 8 to give any desired angle of rotation.

Etching machines of the tank type described and shown in the drawings are in common use but so far as I am aware they all possess the disadvantages and produce the discomforts described above and which my novel improvement entirely overcomes.

Having described the principle of my improvement and two of its several embodiments, I will now state what I claim to be new and novel and for which I desire to secure Letters Patent:

1. An improvement in etching machines for etching photo-mechanical printing plates comprising in combination a holder for the plate to be etched slidably mounted on a vertical guide, a counterweight arranged to counterbalance the weight of the plate holder and its slidably mountings substantially as described.

2. An attachment for use with etching machines of the tank type for etching photo-mechanical printing plates comprising in combination a holder for the plate to be etched slidably mounted on a vertical guide, a counterweight arranged to counterbalance the weight of the plate holder and its slidably mountings substantially as described.

3. An improvement in etching machines for etching photo-mechanical printing plates comprising in combination a holder for the

plate to be etched, means rigidly connecting said holder with a sliding member moveable along a vertical guide, means attached to said sliding member engaging a slot or 5 groove in said guide whereby the movement of said sliding member is directed along said guide.

4. An etching machine for etching photo-mechanical printing plates comprising in 10 combination a chamber for the etching fluid, a rotatable spray-producing member, and a carrier for the plate to be etched slidably mounted on a guide whereby the plate may be entered into and withdrawn from the 15 etching chamber.

5. An etching machine for etching photo-mechanical printing plates comprising in combination a chamber for the etching fluid, a rotatable spray-producing member, and a 20 counterweighted carrier for the plate to be etched slidably mounted on a vertical guide whereby the plate may be entered into and withdrawn from the etching chamber.

6. An etching machine for etching photo-

mechanical printing plates comprising in 25 combination a chamber for the etching fluid, a rotatable spray-producing member and a carrier for the plate to be etched slidably mounted on a guide having means for directing the vertical and rotative motion of 30 the carrier whereby the plate may be entered into and withdrawn from the etching chamber.

7. An etching machine for etching photo-mechanical printing plates comprising in 35 combination a chamber for the etching fluid, a rotatable spray-producing member, and a counterweighted carrier for the plate to be etched slidably mounted on a guide having 40 means for directing the vertical and rotative motion of the carrier whereby the plate may be entered into and withdrawn from the etching chamber.

Signed at Douglaston, in the county of 45 Queens, city and State of New York, this 14th day of December, A. D. 1926.

FRANK T. POWERS.
